CLAIM

The ornamental design for a cart handle, as shown and described.

DESCRIPTION

FIG. 1 is a perspective view of a cart handle showing our new design in an environment of use;

FIG. 2 is a front view thereof;

FIG. 3 is a back view thereof;

FIG. 4 is a top view thereof; and,

FIG. 5 is a left side view thereof, the right side view being a mirror image.

The broken lines shown in FIG. 1 depicts environment and boundary lines that form no part of the claimed design. All other broken lines depict portions of the cart handle that form no part of the claimed design.

1 Claim, 3 Drawing Sheets(56)
